LAWNMOWER CHUTE

William R. Smith, McDonough, and Wallace A. Hanson, Jr., Riverdale, Ga., assignors to McDonough Power Equipment, Inc., McDonough, Ga.

Filed Mar. 29, 1968, Ser. No. 11,198

Term of patent 14 years

U.S. Cl. D40—1

Int. Cl. D15—99

FIG.1

FIG.2

FIG.3

FIG.4

FIG.5

FIG.6

FIGURE 1 is an elevational view of a lawnmower chute embodying our new design as seen from the rear end thereof;

FIGURE 2 is a front end elevational view of the chute taken at 180° from the view of FIGURE 1;

FIGURE 3 is a side elevational view of the chute taken at 90° to the right of the view of FIGURE 1;

FIGURE 4 is a side elevational view of the chute taken at 90° to the left of the view of FIGURE 1;

FIGURE 5 is a top plan view of the chute; and

FIGURE 6 is a bottom plan view of the chute.

The dominant features of the design reside in the full line portions of the drawing.

We claim:

The ornamental design for a lawnmower chute, substantially as shown and described.
